JAMES F. KIELY, OF SYRACUSE, NEW YORK.

RECORDING MACHINE.

Application filed June 15, 1923. Serial No. 645,579.

This invention relates to recording machines, particularly a card time recorder, that is, a recorder in which each person or workman has a daily or weekly time card 5 on which the time of his entering and leaving is printed by the machine, and it has for its object a particularly simple and efficient means for locating the successive records on the card, so that the "in" and "out" records 10 for each day are arranged in successive spaces on the card.

The invention consists in the novel features and in the combinations and the constructions hereinafter set forth and claimed.

15 In describing this invention, reference is had to the accompanying drawings in which like characters designate corresponding parts in all the views.

Figure 1 is a side elevation, partly in section, and parts being removed, of a time recorder mechanism embodying my invention the same being taken on line 1—1, Figure 2.

Figure 2 is a front elevation of the parts seen in Figure 1.

25 Figure 3 is a plan view of the parts seen in Figure 1.

Figure 4 is a sectional view on line 4—4, Figure 3.

Figure 5 is an elevation, parts being omitted, looking toward the left in Figure 2.

30 Figure 6 is a fragmentary plan view of one form of the stop mechanism and contiguous parts.

Figure 7 is a face view of the card.

35 Figure 8 is a fragmentary plan view of another form of the stop mechanism.

Figure 9 is an elevation looking upwardly in Figure 8.

40 Figure 10 is a fragmentary elevation of the operating means looking to the left in Figure 2.

I have here illustrated my invention as embodied in a time recorder, comprising a printing couple including a time stamp element and a card receiver element having relative movement to effect the making of a record on the card and relative lateral movement to locate the records on the card in successive lateral positions, means for effecting 45 such relative movements, and stop mechanism for limiting the lateral movements in successive positions for each card. The stop mechanism is controlled by means of modifications on the card, which means of modi-

fication are placed on the card during each 55 printing operation to control the stop mechanism during the next printing operation on the same card. The card is modified, as by forming a projecting boss thereon during each printing operation, and the modification controls the locating of the record on the card during the next printing operation on the same card. In the illustrated embodiment of my invention, the card receiver is 60 shiftable laterally relatively to the time 65 stamp into different lateral positions. The time stamp includes the usual type wheels 1, supported in a suitable frame 2, and a platen or hammer 3, coacting with the wheels or type on the wheels at the printing line. 70 The time stamp also includes ribbon or inking mechanism and means for operating the platen and effecting the relative lateral positioning of the stamp and the card receiver. The type wheels are actuated from a time 75 movement in any suitable manner as by shaft 4, which shaft is connected to the type wheels in any suitable and known manner.

5 is a card receiver mounted on guide rods 6, 7, supported by the main frame 8 of the 80 recorder and located to support the card between the type wheels 1 and the hammer 3. The card receiver is here shown as provided with a movable abutment 9, against which the lower edge of the card abuts, this abutment being shiftable each day in order to position a different row of the record receiving spaces on the card at the printing line. This card abutment is shiftable each day either automatically or by hand and is here 90 shown as carried by a lever 10 pivoted to the frame 2, having a follower coacting with a scroll 12 which is shiftable either by the time movement or by hand through the rod 13 in any well known manner.

95 The operating mechanism for effecting the making of the record, that is, the actuation of the hammer 3, comprises a prime mover or handle 14 mounted on a shaft 15 supported by the frame to rotate relative thereto, and having a pawl 16 pivoted thereto at 17, the pawl having a tooth or hook 18 arranged to latch on the shoulder 19 (see Figure 10) mounted on a hub 20 keyed to the shaft 15, the pawl being yieldingly held in position 100 to engage the shoulder by a spring 21, and having a tail 22 arranged to engage a knock off shoulder, as a roller 23 supported by a 105

bracket 24 fixed to the main frame. The rocking movement is transmitted to the hammer through a rocker arm 25, Figure 2, keyed to such shaft 15, and the hammer or its shank 26 is pivoted or hinged at 27 to the rocker arm and yieldingly held from pivotal movement by a spring 28, the spring 28 being connected at its ends to hooks on the arms 25 and 26 as clearly shown in Figure 1.

Upon depression of the handle 14, the tooth 18 of the pawl 16 engages the shoulder 19 on the shaft 15 and rocks said shaft thus retracting the hammer until the tail 22 of the pawl 16 engages the roller 23 and moves the pawl 16 on its pivot 17 against the action of its spring 21. Such movement of the pawl lifts the pawl tooth 18 from the shoulder 19 and hence permits the shaft 15 to be returned by the spring 29 and in so doing to throw the hammer in the opposite direction to strike the card and impress it against the type wheels of the machine or the ribbon between the type wheels and the card and thus make a record. The spring 28 permits the hammer to overthrow or flip at the end of its throw after the shaft 15 has been stopped, and to return it rearwardly away from the card, after striking the blow. The rocking of the shaft by the spring 29 is limited by a stop lever 30 mounted on the shaft 15 and having a hub keyed thereto, the stop lever engaging a shoulder as a rod 31, carried by the main frame 8. The spring 29 is connected at one end to the stop lever at 32 and at its other end to a bracket 33 on the main frame 8.

The handle 14 is returned to its starting position by a spring 34, Figure 2, connected at one end to a laterally extending angular arm 35 fixed at 35^a to the handle 14. The return movement of the hammer is limited to its starting position by a shoulder or set screw 36 threading through the bracket 24 in position to engage the downwardly extending arm 37 on the handle. In order to prevent violent operation of the handle 14, controlling means is provided, here shown as consisting of a rocker arm 38 depending from a hub 39 on the shaft 15 and fixed to the handle 14^a stationary rack 40, Figures 2 and 5, on the base of the main frame, a series of cams 41 opposing the rack teeth, and a stop arm 42 movable between the rack 40 and the cams 41 and being normally out of engagement with the rack and having a follower 43 for riding over the cams, the stop arm being connected to the rocker arm 38 by a link 44 pivoted at 45 to the lower end of the arm 38.

Sudden depressing of the handle 14 and hence of the shaft 15, causes the follower 43 of the stop lever 42 to be thrown upwardly by one of the cams 41 against one of the teeth of the rack 40, and thus prevents further movement of the handle until it is again

released. The series of cams 41 and rack teeth 40 require the operator to depress the handle easily, to cause the stop lever to ride over the cams 41 without being thrown into engagement with the rack teeth 40.

The lateral shifting of the card receiver 5 is effected by the handle 14 preliminary to the striking of the blow by the hammer 3, and, as here illustrated, the motion of the handle is transmitted to the card receiver 75 to shift it laterally through a lever arm 46 extending to the rear side of the shaft 15 and forming an extension of the angular arm 35 of the handle 14, a link 47, Figure 5, pivoted at one end at 48 to the lever 46 and at its other end at 49, Figure 2, to one arm of a bell crank lever 50 pivoted at 51 to a bracket 52 on the base of the frame 8, and a lever 53 also pivoted on the same pivot 51 and extending upwardly at one side of the card receiver and connected thereto by a link 54 pivoted at 55 to the upper end of the lever 53 and at 56 to the card receiver, this lever 53 having an angular arm 53^a at its lower end which is connected by a spring 57 to the other arm 50^a of the bell crank lever 50.

Thus, during the depression of the hand lever 14 and the angular arm 35, the lever arm 46, forming an extension of the arm 35, is moved upwardly, pulling the link 47 therewith, and this link moving the bell crank lever 50 causes the motion of said link to be yieldingly transmitted through the spring 57 to the shifting arm 53 connected to the card receiver. During the shifting of 100 the card receiver by the handle 14, the hammer or platen is being retracted and the continued movement of the handle 14 releases the hammer or platen to strike the blow. Thus the card receiver is shifted to its various lateral positions, before the hammer is released from the pawl 16 to strike the blow.

The card receiver is returned to its normal position through the same mechanism during the return of the handle 14 to its starting position by the spring 34, Figures 1 and 5. As this spring is connected to the handle 14 to return it to its starting position, the motion of the handle is transmitted through the arm 46 of the handle, Figure 5, link 47, levers 50 and 53 and link 54. The spring 57 connecting the levers 50 and 53 being under tension during the shifting of the card receiver reacts during the return movement and causes the lever 50 to act on the lever 53 owing to a shoulder or set screw 50^a, Figure 2, on the lever 50 and coaxing with the left edge of the lever 53.

The mechanism controlled by modifications, as bosses, made on the card during 125 each printing operation, comprises two parts, one of which is fixed from lateral movement with the card receiver and the other of which shifts with the card receiver, one of these parts being, for convenience,

called a pawl and the other being provided with a series of successively arranged shoulders corresponding to the positions to be occupied by successive records on the card, 5 this part, for convenience, being called a rack. The parts are arranged so that the shoulders and pawl are normally out of alignment at an angle to the lateral movement of the card receiver and one of them is 10 shifted into alignment with the other part by the modification on the card.

As here illustrated, the rack 58 is shown as fixed to the card receiver, as seen in Figure 6, which is laterally shiftable and 15 the rack is here shown as located on the front side of the card receiver; and the pawl 59 is normally out of the path of the rack teeth and is pivoted at 60 on a vertical pivot to the frame 8, it being formed with laterally folded spaced apart ears 61 at the upper and lower edges of its pivoted end, through 20 which ears the pivot 60 extends, as seen in Figure 1. The pawl 59, as before stated, is normally out of the path of the rack teeth but is normally in the path of a shoulder 62 at the remote end of the series of rack teeth, in order to engage the shoulder 62 without 25 being shifted to limit the lateral shifting of the card in its first or lateral position to locate the first record on the card.

The pawl 59 is controlled in its shifting by means or modifications on the card and, as here illustrated, it is shifted by means of a lever 63, Figures 3 and 6, pivoted at 64 to the cross member 65 on the frame, the lever 63 having a shoulder 66 coacting with the arm 67 of a lever 68 pivoted to the bracket 70, Figure 2, rising from the cross frame member 65, this lever 68 carrying a 40 spring arm 71, having a contact 72 at its end, which makes contact with a terminal 73, carried by a bracket 74 rising from the cross frame member 65. The movement of the lever 68 is against a returning spring 68^a. The arm 71 is connected to one leg 75 of the electric circuit, the other leg 75^a is connected to one end of the coil of an electromagnet 76 suitably supported by the frame; and the terminal 73 is connected by 45 a wire 77 to the other end of such coil. The magnet 76 has suitable armature 78 provided with an angular arm 79 pivoted at 80 to a bracket 81 supported by the main frame, this arm 79 coacting with an arm 82 projecting radially from the pawl 59. When the shifting arm 63 is actuated, as 55 will be presently described, the shoulder 66 moves the lever 68 on its pivot thereby moving the spring arm 71 to carry its contact into engagement with the terminal 73, thus closing the electric circuit, so that the magnet 76 is energized and attracts its armature 78, thereby moving arm 79 against its retracting spring 79^a, and causing said arm 59 to move the arm 82 of the pawl to the

right and shift the pawl 59 into the path of the shoulders of the rack 58 and thus limit the lateral shifting of the card receiver.

The timing of this shifting movement is controlled, as will be presently described. 70 Instead of being electrically operated, the pawl may be shifted mechanically, as shown in Figures 8 and 9, in which the arm 71 is shown as connected mechanically to the pawl 59, the arm 71 being here shown as connected to a bracket 83 rising from the pawl 59, the connection being merely a slot in the bracket 83, which receives the end of the arm 71. A suitable stop 84 limits the movement of the pawl to its starting position in 80 both constructions. In the construction shown in Figures 8 and 9, a spring 85 returns the shifting lever 63 to its starting position.

The means or modifications on the card, to 85 locate the records successively, are preferably placed on the card during each printing operation to control the lateral position of the card receiver during the next operation, this means, as here illustrated, is a 90 punch and either a hole punched through the card or an embossing made on the card.

As will be understood by those skilled in the art, the cards used in time recorders are similar to that illustrated in Figure 7, in 95 which the "in" and "out" registrations for the day of the week are made in a horizontal row and, also, those for each succeeding day are made in a horizontal row below the row of registrations for the next preceding day. 100 During the first registration for any day, the card receiver is shifted to the limit of its lateral movement, that is, until the pawl 59 engages the shoulder 62 of the rack and, for each succeeding registration, the card receiver is shifted a correspondingly shorter distance, in order to place the registrations in successive columns. Also, the card is placed in the card receiver with its face toward the type or in a reverse position from 105 that seen in Figure 7. In this machine, the position of the first registration for any one day is determined by the stop shoulder 62 of the rack 58, during the making of this 110 first registration.

In this embodiment of my invention, the card is modified during the printing of the first record to provide it with means for controlling the shifting of the pawl 59 into the path of one of the shoulders of the rack 115 58, during the shifting of the card receiver to locate the second record; and during the printing of the second record, this card is again modified to control the shifting of the pawl 59 at the proper time to locate the 120 third record, etc.

In the illustrated embodiment of my invention, the card is modified by punching it to form an embossing. The operation with an embossed card will now be de- 125

scribed. The embossing is formed on the card, also, as will be presently described, during the printing operation. During the making of the first record, as that designated 5 6.55 at the top of the first column in Figure 7, the punch mechanism forms the embossing designated at 87, Figures 3 and 7, and, when the card is again placed in the receiver and the handle 14 actuated, the card 10 receiver is shifted to the left, and this embossing, riding along the face 88 of the shifting lever 63, which is located adjacent the rear face of the card, shifts the lever 63 sufficiently to cause the lever 68 to, in turn, 15 actuate the lever 71 to close the circuit to the magnet and, hence, cause the pawl to move into the path of the next to the last tooth 89 of the rack 58 or to cause this arm 71 to actuate the pawl 59 mechanically, as 20 shown in Figures 8 and 9, to shift the pawl into the path of such tooth 89. When the second registration, as 12.01, is made, the punch or embossing 87' is formed on the card in a horizontal line with the first embossing 87, and, hence, when the card is 25 placed in the receiver to make the third registration, as 12.59, this embossing 87' engages and actuates the lever 63, causing the pawl 59 to engage the next tooth 90 of 30 this rack 58. Likewise, the embossing of 87², 87³, and 87⁴ are made successively, engaging the shoulders 91, 92, etc., during the 35 succeeding operations. At the end of each day, the card abutment 9 shifts or is shifted 40 upwardly, so that the next day a new horizontal row of punches or embossings is made on the card.

The means for effecting the modifications of the card, comprises a punch 93, Figures 40 3 and 4, carried by the type wheel carriage, a die 94 opposed to the punch, and a hammer actuated by the handle 14 for striking the die, causing it to coact with the punch to 45 form embossing during the printing operation, that is, while the platen or hammer 3 is coacting with the type wheels. This hammer for operating the punch is similar in its construction and operation to the hammer 3 and, as here shown, comprises an 50 arm 95 mounted on a hub 96 on the shaft 15 adjacent the rocker arm 25, a shank 97 pivoted at 98 to the arm 95, and a spring 99 connecting the parts 95 and 97, so that the 55 shank 97 can flip relatively to the arm 95 when the shaft 15 is limited in its movement. The hub 96 is loose on the shaft 15 and said arm 95 is actuated by an extension 100 of the pivot of the hammer arm or shank 26 such actuation being against a spring 101. 60 A stop 102 limits the movement of the arm 95 by the spring. The extension 100 of the pivot 27 of the hammer extends through a slot in the arm 95 of the punch hammer 97 so that actuation of the hammer arm 26 65 causes this extension 100 of the pivot 27 of

the hammer arm 26 to carry the arm 95 of the punch hammer backwardly with it. The slot in which the pin 100 is located permits the punch hammer to flip against the action of the spring 99. As before described, during the operation of the hammer 3, the upper end of the shank 97 strikes against the die 94 and moves it against the card interposed between the punch 93 and the die, causing the embossing 87 to be made. The 70 die, as here shown, is the head of the lever 63, the head being opposed to a yieldingly mounted anvil 103, carried by the type wheel carriage adjacent the punch 93, the movement of the anvil being against a suitable 75 cushioning spring 104. The hammer strikes at one side of the die cavity and, in operation, the head of the lever 63 is moved by the shank 97 against the card and the card against the anvil 103 which yields during 80 the striking of the blow. During the movement of the head of the lever 63 and the yielding of the anvil, the die cavity is brought against the card opposite the point, the card is engaged by the punch, so that 85 during the striking of the blow the card is provided with a punch or embossing.

By my stop mechanism, the card receiver or other shiftable element is limited by modifications on the card placed on the card during 90 the preceding printing operation and, hence, successive records on each card are governed by the conditions present in that card only.

What I claim is:

1. In a recording machine the combination of a printing couple comprising a stamp element and a card receiver element having relative movement to effect the printing of a record on the card in the receiver and relative lateral movement to locate the record on the card, operating means for effecting such relative movements, stop mechanism for limiting the lateral movement in successive positions, mechanism operated by the relative movement of the printing couple elements while making a record to produce a modification in the form of a boss projecting out of the plane of the card for controlling the operation of the stop mechanism during the next printing operation on the card, said stop mechanism comprising a part located out of the plane of the card and in the path of the boss to be engaged and shifted thereby, during the lateral movement of the card receiver.

2. In a recording machine the combination of a printing couple comprising a stamp element, and a card receiver element having relative movement to effect the printing of a record on a card in the receiver and relative lateral movement to locate the record on a card, operating means for effecting such relative movements, stop mechanism for limiting the lateral movement in successive

lateral positions, mechanism associated with the printing couple and operated by the relative movement thereof while making a record, to produce a modification on the 5 card in the form of a boss projecting out of the plane of the card, for controlling the operation of the stop mechanism during the next printing operation on the card, said modification producing mechanism forming 10 a series of bosses in a row on the card, one boss during each printing operation, and the stop mechanism comprising a movable part arranged out of the plane of the card and in the path of the bosses, each boss acting 15 as a cam to actuate said part during the said operation.

3. In a recording machine the combination of a printing couple comprising a stamp element and a card receiver element having 20 relative movement to effect the printing of a record on a card in a receiver, and relative lateral movement to locate the record on a card, operating means for effecting such relative movements, stop mechanism for limiting 25 the lateral movements in successive lateral positions, mechanism associated with the printing couple and operated by the relative movement thereof while making a record to produce a modification on the card 30 in the form of a boss projecting out of the plane of the card for controlling the operation of the stop mechanism during the next printing operation on the card, said modification producing mechanism, forming a 35 series of bosses in a row on the card, one

boss during each printing operation, and the stop mechanism comprising a lever arranged to be operated by the boss on the card, the boss acting as a cam on the lever to actuate it.

4. In a recording machine the combination of a printing couple comprising a stamp element, and a card receiver element having relative movement to effect the printing of a record on a card in a receiver and relative lateral movement to locate the record on 40 a card, operating means for effecting such relative movements, stop mechanism for limiting the lateral movements in successive lateral positions, mechanism associated with the printing couple and operated by the 45 relative movement thereof, while making a record to produce a modification on the card in the form of a boss projecting out of the plane of the card for controlling the operation of the stop mechanism during the next 50 printing operation on the card, said modification producing mechanism forming a series of bosses in a row, one boss during each printing operation, and the stop mechanism comprising a lever arranged to be operated 55 by the boss on the card and the boss acting as a cam on the lever to actuate it, and a rack and pawl, the pawl being connected to the lever to be operated by the lever.

In testimony whereof, I have hereunto 60 signed my name, at Syracuse, in the county of Onondaga and State of New York, this 31st day of May, 1923.

JAMES F. KIELY.
